UNITED STATES PATENT OFFICE.

SAMUEL ARDELL FORCEY, OF DU BOIS, PENNSYLVANIA.

DESIGN FOR A GLASS REFLECTOR FOR ELECTRIC-LIGHT FIXTURES.

Application filed May 20, 1924. Serial No. 9,666. Term of patent 3½ years.

To all whom it may concern:

Be it known that I, SAMUEL ARDELL FORCEY, a citizen of the United States, residing at Du Bois, in the county of Clearfield and State of Pennsylvania, have invented a new, original, and ornamental Design for Glass Reflectors for Electric-Light Fixtures, of which the following is a specification, reference being had to the accompanying drawing, forming a part thereof.

Figure 1 is a bottom plan view of a reflector showing my design; Figure 2 is a sectional view taken on the line A—A of Figure 1; and Figure 3 is a sectional view on the line B—B of Figure 1.

I claim:

The ornamental design for a glass reflector for electric light fixtures, substantially as shown.

SAMUEL ARDELL FORCEY.
